UNITED STATES PATENT OFFICE.

ISOM L. MARSH, OF LOS ANGELES, CALIFORNIA, ASSIGNOR OF ONE-HALF TO JOHN C. BURNETT, OF FULLERTON, CALIFORNIA.

ARCH CONSTRUCTION.

1,177,257.

Specification of Letters Patent. Patented Mar. 28, 1916.

Application filed August 16, 1915. Serial No. 45,675.

To all whom it may concern:

Be it known that I, ISOM L. MARSH, a citizen of the United States, residing at Los Angeles, in the county of Los Angeles and State of California, have invented new and useful Improvements in Arch Construction, of which the following is a specification.

This invention relates to an arch construction, and particularly pertains to a fire-back arch for boilers.

In the ordinary construction of fire-back arches for stationary boilers, the arch is built up of masonry which, when it is desired to gain access to the space at the rear end of the boiler, is usually torn down. This requires considerable time and labor, with a waste of materials and frequently necessitates the boiler being shut down for a considerable period of time.

It is the object of this invention to provide an arch construction of the above character which will permit of ready access to the space at the rear end of the boiler without demolition of the arch and which may be opened and closed within a few moments, with a consequent expenditure of little time, labor and expense.

Another object is to provide a fire-back arch for boilers having a fire-brick lining or facing built up in sections and in which a section may be removed and replaced when damaged without wrecking the arch.

Another object is to provide a metallic support having a plurality of lining members in fire-back arch construction, so constructed and arranged that the metallic supports will not be subjected to the direct heat beneath the arch.

A further object is to provide a sectional fire-back arch for boilers which is simple in construction and economical in manufacture and which may be readily applied and substituted for the arch construction now generally in use.

The invention primarily resides in providing a movable lining-supporting bar and producing fire-back tile or brick lining members adapted to be removably and interchangeably attached to the supporting bar; a plurality of the bars and the fire-back members thereon being ordinarily employed in forming a single arch, the invention being illustrated in the accompanying drawings in which:

Figure 1 is a view in section and elevation

illustrating the application of the invention to a stationary boiler. Fig. 2 is a plan view of the rear end of a boiler showing the arch construction as applied. Fig. 3 is a detail transverse section through the arch showing the manner of interlocking adjacent fire-back sections. Fig. 4 is a view of the arch in side elevation. Fig. 5 is a view of same in end elevation. Fig. 6 is a view in perspective of an under-lapping fire-back section. Fig. 7 is a view in perspective of an over-lapping fire-back section. Fig. 8 is a view in vertical section showing the manner of interlocking the ends of adjacent fire-back sections. Fig. 9 is a detail in cross-section showing the manner of interlocking transversely adjacent fire-back sections, and illustrating the manner in which the fire-back sections are removably attached to their supporting members. Fig. 10 is a view illustrating a modified form of connection between the fire-back sections and the supporting member.

More specifically, 12 indicates a stationary boiler which is suitably supported and has a fire-box 13 formed therebeneath closed at the sides by walls 14 and 15 which extend upward alongside of the boiler 12 and connect with an end wall 16 spaced from the rear end 17 of the boiler. The walls 14, 15 and 16 are usually constructed of masonry.

The present invention resides in a structure for forming an arch or closure extending from the end wall 16 to the rear end 17 of the boiler 12 to direct heat and products of combustion from a chamber or space 18 in front of the wall 16 through the flues 19 of the boiler.

In carrying out the invention the walls 14 and 15 are preferably carried above the wall 16, as particularly shown in Fig. 1, to form an abutment for the arch which extends between the walls 14 and 15 and abuts against the rear end of the boiler 12. In forming the arch, a movable supporting member or bar 20 is provided which is here shown as attenuate in form, one end of which is adapted to seat on the wall 16 with its opposite end abutting against the rear end of the boiler 12 or against inwardly extending productions on the walls 14 and 15, as shown in Fig. 2.

The supporting member 20 is preferably formed of cast metal and has a laterally projecting portion 21 extending through-

out its length formed with a central upwardly extending web 22. The supporting member has a longitudinally extending dove-tailed open-ended slot or channel 23 formed on its inner arcuate face. This channel is designed to receive dove-tailed ribs 24 formed on the upper faces of the lining member 25, or slabs as particularly shown in Fig. 9. The lining members 25 are formed of fire-brick or similar material and are curved longitudinally to conform with the inner face of the supporting member 20; a series of the lining members being designed to be mounted on the supporting member to extend the length thereof, as shown in Fig. 4.

In carrying out the present invention, the lining members are provided in two slightly different shapes, as shown in Figs. 6 and 7 and herein designated as underlapping and overlapping members 26 and 27 respectively. The lining members are rectangular in outline and are formed with an overlapping flange 28 on their lower edges and an underlapping flange 29 on their upper end edges; the flanges 28 on one lining member being adapted to extend over the flanges 29 on the adjacent lining member when assembled on a supporting member 20 as shown in Figs. 4 and 8. The lining members 26 are designed to be mounted on one supporting member 20 and the lining members 27 are to be mounted on adjacent supporting member, and to be positioned alongside of the lining members 26.

As a means for closing the joint between the adjacent lining members, the members 26 are formed with side flanges 30, and members 29 are formed with side flanges 31, adapted to extend over the flange 30, as shown in Fig. 9; a pair of supporting members and the interconnecting lining slabs thereon forming an arch unit which may be multiplied indefinitely to form an arch of any length.

The supporting members 20 may be pivotally mounted so that they can be swung back clear of the boiler 12 as shown in Figs. 1 and 2. For this purpose, lugs 32 are formed on the lower portion of the web 22, which are adapted to extend between lugs 33 formed on a plate 34 carried by the wall 16, removable pivot pins 35 connecting the lugs 32 and 33 to form a hinged joint on which the supporting member 20 may be swung vertically. The webs 22 are formed with handholes 36 adjacent their upper ends by means of which they may be readily grasped and swung in or out of the operative positions.

In assembling the arch in accordance with this invention, a plate 34 is laid on the wall 16 and has a series of supporting bars 20 pivotally connected thereto; a sufficient number of the members 20 being provided that

when the latter are fitted with the lining members, these lining members will extend across the space between the walls 14 and 15 at the rear end of the boiler. A series of the lining members 26 are then mounted on the second supporting member 20 from the end; being put in place by introducing the ribs 24 on the lining members in the open end of the channel 23 of the supporting member, while the latter is in its retracted position. The supporting member is then swung forward in its operative position. A series of the lining members 26 is then placed on the alternate supporting member and the latter disposed in its operative position; the alternating supporting members thus being first fitted with lining members and placed in position throughout the length of the arch. The adjacent supporting members 20 are then provided with the lining members 27 and when disposed in their forward position, the lining members 27 overlap the lining members 26, as particularly shown in Fig. 3, thus completing the arch.

When it is desired to gain access to the space beneath the arch, the supporting member 20 carrying the lining members 27 is rocked into its retracted position as shown in Fig. 1. If it is desired to remove or replace any of the lining members, this is readily accomplished by retracting the supporting member and removing one or more of the lining sections therefrom, as required.

In the modified form of the invention, as shown in Fig. 10, the supporting member 20 is provided with longitudinal ribs 37 on its edges, which are adapted to engage overhanging flanges 38 formed on the backs of the members 25.

While I have shown the arch as formed of arcuate members, it is manifest that they may be constructed of any other form, such, for instance, as straight, where a flat arch is desired. By disposing the lining members on the inner face of the supporting members, the latter are protected from direct contact with the heat in the chamber 18 and are thus prevented from being warped or burned out.

From the foregoing, it will be seen that I have provided a simple arch construction which can be readily assembled and parts removed and replaced without demolition of the arch and which facilitates access to the space beneath the arch.

While I have shown the arch as formed with a plurality of lining members and a single supporting member, it is manifest that in some instances, particularly where the span of the arch is small, that a single lining member of the desired length of span of the arch may be employed. It is also obvious that the overlapping connection between the adjacent lining members

may be formed in any suitable manner and in some instances may be dispensed with.

I claim:

1. An arch construction, comprising a pair of supporting members, a pivotal mounting therefor, and a plurality of lining members slidably connected to said supporting members with the lining members of one supporting member overlapping the lining members of the other supporting member.

2. An arch construction comprising a pair of supporting members, a pivotal mounting therefor, and a plurality of lining members detachably connected to said supporting members with the lining members of one supporting member overlapping the lining members of the other supporting member.

3. An arch construction comprising a pair of arcuate supporting members, a pivotal

mounting for said members and arcuate lining members slidably and detachably connected to said supporting members and so formed that the lining members on the adjacent supporting members will overlap each other.

4. An arch construction comprising a plate, a series of supporting members pivotally connected to said plate adapted to be swung vertically, an abutment for the outer ends of said supporting members and lining members carried on the under sides of said supporting members, said lining members formed with marginal flanges adapted to overlap coöperating flanges on contiguous lining members.

In testimony whereof I have signed my name to this specification.

ISOM L. MARSH.
